UNITED STATES PATENT OFFICE.

DANIEL W. COLBY, OF BOSTON, MASSACHUSETTS, ASSIGNOR TO UNITED SHOE MACHINERY COMPANY, OF PATERSON, NEW JERSEY, A CORPORATION OF NEW JERSEY.

MACHINE FOR SETTING EYELETS OR SIMILAR FASTENERS.

1,191,926.

Specification of Letters Patent. Patented July 18, 1916.

Application filed October 12, 1911. Serial No. 654,241.

To all whom it may concern:

Be it known that I, DANIEL W. COLBY, a citizen of the United States, residing at Boston, in the county of Suffolk and State of Massachusetts, have invented certain Improvements in Machines for Setting Eyelets or Similar Fasteners, of which the following description, in connection with the accompanying drawings, is a specification, like reference characters on the drawings indicating like parts in the several figures.

This invention relates to machines for setting eyelets, lacing hooks or similar fastening devices and consists in certain improvements designed to adapt such machines for setting D-shaped eyelets and in other improvements designed to adapt such machines for operations by foot power.

One object of the invention is to provide improved mechanism for shifting the raceway into and out of alinement with the setting dies for delivering fasteners thereto, which mechanism shall be operated from the main actuating lever of the machine.

To this end an important feature of the invention consists in the combination with the actuating lever for the setting die, of a bodily movable cam connected with the raceway and so shaped that it will impart an irregular movement to the raceway beginning after the initial movement of the setting die and, if desired, terminating before the end of the lever movement. In this way the actuating lever may have a stroke of sufficient extent to impart a powerful pressure to the setting dies while the motion of the raceway need not be more than sufficient to carry its delivery end out of alinement with the dies.

The invention is herein disclosed as embodied in a machine for setting D-shaped eyelets and to this end certain parts of the machine are peculiarly shaped. For example, the setting dies are made substantially D-shaped in cross section and are disposed with their flat sides toward the front of the machine. The raceway, which extends from front to back, is so shaped as to deliver the D-shaped eyelets in corresponding position. Mechanism of this character constitutes a further feature of the invention. It will be apparent, however, that the invention is not limited in its broad application

to machines for setting eyelets of any particular shape.

The features of the invention will be best understood and appreciated from the following description of a preferred embodiment thereof selected for purposes of illustration and shown in the accompanying drawings in which,

Figure 1 is a view of the machine in side elevation; Fig. 2 is a fragmentary view showing the setting dies and the delivery end of the raceway. Figs. 3 and 4 are fragmentary views in perspective of the assorting mechanism; Fig. 5 is a fragmentary sectional view on the line 5—5 of Fig. 3; and Fig. 6 is a fragmentary sectional view on the line 6—6 of Fig. 3.

As herein shown the machine comprises a flat base plate 10 from which extends a vertical frame 12 and an ear 22 located on one side of the frame and spaced a short distance from it. The frame 12 is bifurcated and is provided in its upper arm with a socket for the upper setting die 14. In the lower arm of the frame 12 is provided a vertical bearing for the plunger 16 which carries at its upper end the lower setting die 18. The lower setting die 18 is provided with the usual center spindle 20.

The plunger 16 is actuated by means of the lever 24 which is journaled on a pin extending transversely between the ear 22 and the frame 12. The lever 24 is forked at its forward end to receive a transverse pin 26 mounted in a slot in the lower end of the plunger 16 and is provided with bosses on each side of its axis which contact with adjustable stops on the base plate 10 and determine the limits of the movement of the lever.

The raceway 36 is supported pivotally upon the upper ends of the lever 30 and link 32 and is movable from an initial position, in which the endmost eyelet in the raceway is located in alinement with the spindle 20 of the lower setting die, as shown in Fig. 2, to an inoperative position to the rear of the setting dies.

The eyelet hopper is mounted upon the rear end of the raceway and carried back and forth by the raceway in its oscillations. The hopper herein disclosed is provided with a rotatable casing 40 having a driving shaft

44 extending downwardly through the bottom of the hopper and provided at its lower end with a ratchet wheel 45. As the hopper is moved back and forth with the raceway the teeth of the ratchet wheel 45 are engaged by a relatively stationary pawl mounted upon the boss 46 on the frame 12 and the casing 40 thus rotated.

Movement of the raceway is effected by 10 the oscillation of the lever 24 through a cam and roller connection. As herein shown the lower end of the lever 30 is provided with a plate 34 in which is cut an interior cam surface. The lever 24 is offset outwardly at 15 the rear of its pivot and passes outside the end of the raceway lever 30, being provided with a roller on its inner side mounted on a stud 28 and arranged to project into the cam in the plate 34. The shape of the cam is 20 such that during the first part of the working stroke of the lever 24 lost motion occurs between the roller and the cam so that the end of the spindle 20 is raised sufficiently to impale the endmost eyelet before any 25 movement of the raceway occurs. After the eyelet has been thus engaged the roller encounters a projection in the cam surface and the raceway is moved into its inoperative position. After the raceway has been so moved 30 further lost motion takes place between the roller and the cam during which the clenching movement of the lower setting die takes place. The position of the cam and roller at this time is indicated in dotted lines in 35 Fig. 1. The lever 24 is actuated by a treadle rod 25 and at the completion of the setting operation a spring 27 connected with the treadle rod acts to elevate the rear end of the lever 24 and retract the lower setting die. 40 During the first part of the reverse movement of the lever 24 the roller traverses the rear side of the cam without moving the raceway and during this period the lower setting die is lowered below the path of the raceway. When the lower setting die has 45 nearly reached its lower position the roller encounters the upper surface of the cam and the raceway is moved forwardly to its initial position. It will be seen that the cam in the 50 plate 34 co-operates with the roller on the lever 24 in such a way as to impart an irregular movement to the raceway which terminates before the end of the working stroke of the lever while the setting die is uniformly moved by the lever. The raceway is 55 held against movement while the roller is not acting on the cam 34 by a friction plug on the link 32 which engages a plane raised surface 33 on the frame.

60 As has been stated above, the illustrated machine is adapted for setting D-shaped eyelets. To this end the setting dies 14 and 18 and also the center spindle 20 are made D-shaped in cross section, as shown in Fig. 65 2. The straight sides of the setting dies are

disposed toward the front of the machine so that the D-shaped eyelets shall be set with their curved sides toward the edge of the work. In order to deliver the eyelets in the proper position to the setting dies the delivery end of the raceway is curved transversely across the machine and has an opening in its side through which the endmost eyelet is drawn by the center spindle 20 when the raceway is moved rearwardly. 70 The endmost eyelet is yieldingly retained in the raceway by a leaf spring 38 which extends over the end of the barrel of the eyelet and has a hooked portion arranged to engage the outer flat surface of the barrel. 75

Referring now to the eyelet assorting device, as shown in Figs. 3 to 6, the circular base plate 42 is provided with a depressed track or channel 50 having on its inner edge a vertical shoulder. A cylindrical casing 40 is arranged to turn with its lower edge on the track 50 and is actuated from the central shaft 44 to which it is connected by radially extending arms. In the lower edge of the casing 40 are formed a plurality of open ended U-shaped recesses 48 the walls of which are tapered inwardly from the inner surface of the casing. These recesses are each shaped to receive a D-shaped eyelet resting on its flat side and receive the eyelets from the mass contained promiscuously in the hopper. The upper end of the raceway 36 merges into the track 50 through an intermediate piece 54 which has cut in it a track so shaped as to tilt each eyelet passing 80 over it endwise so that it shall rest on its flange. To this end the portion of the track on which the barrel of the eyelet rests is given a gradually increasing pitch as it approaches the upper end of the raceway and the front wall of the track is correspondingly flattened as will be apparent from the sectional views shown in Figs. 5 and 6. On account of the inclination of the raceway and hopper the eyelets would drop out of the 85 recesses 48 as they approach the rear side of the hopper if not retained by the shoulder of the track 50. In order to prevent eyelets of the mass from reaching the raceway through the opening cut in the base plate 42 for the piece 54 an angular guard plate 52 is provided at this point as shown in Figs. 90 3, 5 and 6.

The eyelet assorting mechanism above described is not claimed herein but forms the 120 subject-matter of a divisional application Serial No. 39,207, filed July 10, 1915.

It is believed that the operation of the machine will be clear from the foregoing description but it may be briefly stated as 125 follows: Eyelets are poured promiscuously into the hopper and such as happen to assume proper positions enter the recesses 48 at the lower side of the casing 40 and are carried to the upper end of the raceway by 130

the rotation of the casing, being turned end-
wise so as to rest on their flanges as they
pass over the track in the section 54. The
previously punched work is threaded over
5 the upper setting die and the treadle rod de-
pressed whereupon the center spindle en-
gages an eyelet in the raceway, the raceway
is retracted and the eyelet is carried up-
wardly, inserted in the work and clenched
10 against the stationary setting die. The
treadle rod is then released and the lower
setting die retracted by the spring 27 leav-
ing the work free to be removed.

Having thus described my invention what
5 I claim as new and desire to secure by Let-
ters Patent of the United States is:—

1. A machine for setting fasteners hav-
ing, in combination, a reciprocatory setting
die at the front of the machine, a raceway
10 supported near its forward end by an angu-
lar lever having one arm extending toward
the rear and provided with a closed cam, an
actuating lever for the die having a co-
operating cam roller located at the rear of
25 its fulcrum and projecting into the cam,
and adjustable stops for limiting the ex-
treme positions of the actuating lever.

2. A machine for setting D-shaped eye-
lets, having, in combination, a raceway ex-
30 tending from the back toward the front of
the machine and having its delivery end
curved transversely whereby D-shaped eye-
lets may be presented with the flat side of
35 each eyelet disposed substantially at right
angles to the length of the raceway as a
whole, coöperating setting dies of D-shaped
cross section disposed with their flat sides
also substantially at right angles to the
40 length of the raceway, and a yielding stop
arranged to engage the barrel of the end-
most D-shaped eyelet in the raceway.

3. A machine for setting fasteners hav-
ing, in combination, a reciprocatory setting
die, a raceway mounted on pivoted support-
45 ing members one of which comprises an angu-
lar lever having a closed cam formed in
its end remote from the raceway, said cam
having dissimilar oppositely disposed sur-
faces for imparting movements in opposite
50 directions and of different timing to the

raceway during the uniform movements of
the setting die, and a movable roller for
moving the cam.

4. A machine for setting fasteners, hav-
ing, in combination, a frame, a reciprocatory 55
setting die mounted therein, an ear arranged
parallel with one side of the frame, an actu-
ating lever pivotally mounted between said
frame and ear and connected at its forward
end to said setting die and having an offset 60
portion in its rear end, a movable raceway,
and a cam connecting said lever and race-
way at the rear of the axis of the lever and
in the offset portion thereof.

5. A machine for setting D-shaped eye- 65
lets, having, in combination, coöperating D-
shaped setting dies disposed with their flat
sides toward the front of the machine, a
raceway extending from the back toward
the front of the machine and having its de- 70
livery end curved transversely of the ma-
chine and opening toward the front whereby
a D-shaped eyelet may be presented with its
flat side toward the front, and a yielding
stop extending over the barrel of the end- 75
most eyelet in the raceway and engaging its
flat side.

6. A machine for setting fasteners hav-
ing, in combination, a movable die, a vibrat- 80
ing raceway associated therewith, an actu-
ating lever for the die, and a cam arranged
to constitute a connection between the race-
way and lever, said cam having two portions
on the same effective side arranged to be 85
disposed concentrically with respect to the
axis of the actuating lever during its work-
ing stroke, whereby the raceway may re-
main at rest during the initial and final part
of the movement of the lever, and having 90
also an intermediate portion of limited ex-
tent so disposed as to cause the raceway to
be shifted during the intermediate part of
the movement of the lever.

In testimony whereof I have signed my
name to this specification in the presence of 95
two subscribing witnesses.
